[57] CLAIM

The ornamental design for a convertible picnic table, as shown and described.

DESCRIPTION

FIG. 1 is a perspective view of my new design for a convertible picnic table.

FIG. 2 is a side view of the table as viewed from the right of the full figure view of FIG. 3.

FIG. 3 is an end view of the table.

FIG. 4 is a top plan view of the table.

FIG. 5 is a side view of the table as seen from the left in FIGS. 1 and 3.

FIG. 6 is a perspective view illustrating the table converted for use as a bench.

FIG. 7 is an end view of the device as used for a bench or seat.
